Inventor:
John Butter

UNITED STATES PATENT OFFICE.

JNO. BUTTER, OF BUFFALO, NEW YORK.

IMPROVED MOWING-MACHINE.

Specification forming part of Letters Patent No. 20,479, dated June 8, 1858.

To all whom it may concern:

Be it known that I, JOHN BUTTER, of Buffalo, in the county of Erie and State of New York, have invented a new and Improved Mowing-Machine; and I do hereby declare that the following is a full and exact description thereof, reference being had to the accompanying drawings, and to the letters of reference marked thereon.

The nature of my invention relates, first, to an improvement in the construction of the frame, so as to give the machine the feature of flexibility when mowing and adjustability for reaping; second, in the construction and arrangement of a wheel to carry the inner end of the finger-bar, so that the wheel will tread on a line with the finger-bar and allow the cutter-bar to vibrate through the wheel; third, in so constructing the guard-fingers that they may be connected to the finger-bar, and support the finger-bar clear from the ground, and allow the cutter-bar to work on the under side of the finger-bar; fourth, in the mode of supporting and adjusting the driver's seat on the axle of the driving-wheel; fifth, in the mode of supporting and adjusting the raker's seat; sixth, in the arrangement of the wheel, divider, and spring to be used on the outer end of the finger-bar.

To enable others skilled in the art to make and use my invention, I will proceed to describe the construction and operation of the same.

Figure I is a perspective. Fig. II is a plan of the under side of the guards, cutters, finger-bar, and carrying-wheels, as arranged together. Fig. III is a section through the plane X Y. Fig. IV is an elevation of a guard-finger, showing also a transverse section of the cutter-bar and finger-bar. Fig. V is a transverse section of the carrying-wheel. Fig. VI is an elevation of the same.

A B, Fig. I, represent the main supporting-timbers of the frame. The finger-bar is attached to these timbers.

C D E are a series of jointed levers, which support the driving-wheel and give flexibility to the machine. C is connected to the timber B by joint at b. E is connected to the shaft G by means of a sleeve. A broad circular plate or brace, F, projects from the journal-cap h y and prevents it from swaying. D is connected to C by means of the shaft d². E

connects with the shaft of the driving-wheel by means of the sleeve r r, Fig. III. This sleeve turns on the shaft, and the driving-wheel turns on this sleeve. D also connects with the shaft of the driving-wheel and turns thereon, and by means of its large circular rim t² t², in connection with a similar rim, r² r², on E, they form a perfect support for the driving-wheel and prevent it from swaying.

H H represent bars of spring metal, and which, with the cross-pieces i i, make the driver's seat. These bars are connected to the axle of the driving-wheel, one on each side, and turn thereon by means of a sleeve for each bar. Each sleeve has notches cut in the edge thereof, through which a pin, h, passes, and also through the axle of the driving-wheel. By means of these notches and pins the driver's seat is made adjustable. The weight of the driver is thus brought directly onto the driving-wheel, and is equally balanced thereon.

J is the adjustable seat for the raker; K, driving-wheel.

L is the carrying-wheel. This consists of an outside revolving rim, L, and an inside supporting-segment, l² l², Fig. V. The rim L is supported and revolves upon the segment l², corresponding bevels being made on the rim and segment, as represented at n n, Fig. V. A standard, y, is bolted onto the finger-bar, and supports the segment and rim. The wheel will have a vertical movement in this standard, as indicated by the slot s. The segment is made in two parts and riveted together. Fig. VI shows more distinctly the openings O', through which the cutter-bar vibrates. This wheel is designed to carry the finger-bar and relieve its drag upon the ground. It is so constructed that it can work on a line with the finger-bar and allow the cutter-bar to vibrate through it. A similar wheel is connected to the outer end of the finger-bar.

N represents the outside shoe or divider.

O represents a spring and cover for the wheel. This is connected to the point of the divider, as seen at s t, and to the segment of the wheel, as seen at r t.

M represents an iron finger-bar.

P is the guard-finger. This is cast in two parts. The bottom part has a broad recess for the reception of the cutter-bar and the escape of all clogging matter, as represented at m, Fig. IV, and an extension backward for the

purpose of connecting to and supporting the finger-bar, as represented at m^2 . The upper part is jointed to the under part, as represented at s^3 . This joint is for the purpose of rendering more easy the fitting of the guard to the finger-bar. The two parts may be riveted together, instead of the joint, if preferred. The guards have lateral projections, so that when arranged on the finger-bar they will brace each other on the bottom, as represented at $p\ p$, Fig. II. The finger-bar rests upon the guards and does not touch the ground.

g represents steady-pins to hold the cutter-bar in place; W , sleeve to which the spring-bars H are attached; W^2 , axle of driving-wheel; Z , pin which passes through the rims of the levers D and E and holds them rigid when the machine is used for reaping; V , Fig. II, cutter-bar; V^2 , Figs. III and I, cog-rim of driving-wheel.

The gearing for driving the cutters is arranged in a common and well-known manner. The arrangement of the jointed levers $C\ D\ E$ and the support of the driving-wheel thereon enables the finger-bar and cutters to conform to the uneven surface of the ground without reference to the tread of the driving-wheel. The arrangement also enables me to raise and lower the finger-bar and cutters on a vertical line and fix them at any height, by means of the pin Z , for reaping, the outside wheel, L , being also adjustable. When the machine is used for reaping a platform is attached.

I claim—

1. The combination and arrangement of the jointed levers $C\ D\ E$, for the purpose of supporting the driving-wheel and giving flexibility to the machine, substantially as herein set forth.
2. The arrangement of the carrying-wheel L near the heel of the cutter-bar, so that the finger-bar will pass through the wheel and the cutter-bar or connecting-rod also vibrate through the wheel, substantially as herein described.
3. Constructing the guard-fingers so that they may be connected to the finger-bar and support it clear from the ground, and also allow the cutter-bar to work on the under side of the finger-bar, as herein set forth.
4. The sleeve W , when connected with the spring-bars $H\ H$, for the purpose of supporting and adjusting the driver's seat on the axle of the driving-wheel, as herein described.
5. The arrangement and support of the raker's seat on the lever C , as herein set forth.
6. Supporting and carrying the outer end of the finger-bar by means of the specific arrangement of the divider N , wheel L , and spring O , as herein described.

JOHN BUTTER.
